UNITED STATES PATENT OFFICE.

SAMUEL MOORHOUSE, OF LEEDS, ENGLAND, ASSIGNOR TO FAIRBAIRN LAWSON COMBE
BARBOUR LIMITED, OF LEEDS, ENGLAND.

DOFFING APPARATUS FOR SPINNING, DOUBLING, TWISTING, AND LIKE MACHINES.

Application filed June 29, 1927, Serial No. 203,334, and in Great Britain July 6, 1926.

My invention relates to doffing apparatus for spinning, doubling, twisting and like machines of the type known as "flyer frames" and my present invention consists
5 in the employment of devices which I arrange to be actuated by the lifter shaft to secure the removal of the full bobbins from the spindles by lowering the lifter plate, the retraction of the empty bobbin holders from
10 the positions they normally occupy beneath the spindles during spinning to permit the said lowering of the lifter plate to be carried out, and the subsequent advancing of the empty bobbin holders to displace the
15 full bobbins, while the reversal of the movements of the lifter plate to restore it to its operating position secures the placing of the empty bobbins upon the spindles, the retraction of the empty bobbin holders to allow
20 the raising of the lifter plate and the final advance of the empty bobbin holders into their normal positions during the spinning operations. In connection with the above
25 devices in accordance with my invention I make use of means for operating the drag cords, devices for adjusting the flyers, cam
30 operated bifurcations for clearing or removing any coils of threads that may encircle the spindles, a slotted rod for receiving the
35 threads so that the attendant may cut or sever said threads by drawing a knife along same, an adjustable receptacle for the full bobbins and coupling and brake devices for permitting the spindles to rotate under conditions which are hereinafter explained.
40 In order that my said invention may be readily understood I have hereunto appended sheets of drawings illustrative thereof to which by figures and letters, reference is
45 made in the following description:—

Fig. 1 is a front elevation of sufficient of a flyer spinning frame to show the application thereto of my improved parts. The view is of the left hand end of the machine where the hand wheel for carrying out the doffing process is mounted.

Fig. 2 is a plan of the parts shown by Fig. 3.

Fig. 3 is a front elevation of a device 50 mounted upon the lifter rail for operating the drag cords as is hereinafter described.

Fig. 4 is a sectional plan showing certain of the parts illustrated by Fig. 1.

Fig. 5 is a sectional plan of the devices which I employ for bringing all the legs of 55 the flyers into the same vertical plane or approximately so.

Fig. 6 is a front elevation showing devices to the rear of the spindles, which I employ for removing the coils of yarn from 60 off the spindles when same have been left thereon by the descending bobbins during the process of doffing. The spindles are omitted from this view in order that the said devices may be more clearly seen. 65

Fig. 7 is an end elevation of certain of the parts shown by Fig. 1 and as seen looking from left to right of said figure.

Fig. 8 is a front elevation showing certain of the parts at the opposite end of the machine to that shown by Fig. 1. 70

Fig. 9 is a sectional plan of certain of the parts shown by Fig. 8.

Fig. 10 is a sectional end elevation of the parts shown by Fig. 8 as seen looking from 75 left to right of said figure.

Fig. 11 is a sectional plan showing certain devices hereinafter described.

Fig. 12 is a front elevation illustrating the devices shown by Fig. 5, which act upon the flyers as described in connection with said Fig. 5. 80

Fig. 13 is a sectional elevation showing the parts illustrated by Fig. 12 as seen looking from right to left of said figure. 85

Fig. 14 is a sectional end elevation showing the devices illustrated by Fig. 6 as seen looking from right to left of said figure.

Fig. 15 is a similar sectional elevation to Fig. 14 but illustrates the device for engaging with the empty bobbins and for carrying same forward. 90

A¹ indicate the two end frames of the machine.

The devices known as the "lifter mechanism" which I make use of are of the type wherein cam mechanism causes a horizontal shaft to oscillate so that by chains taking over chain pulleys fixed thereon, the rising and descending or vertically reciprocatory motions of the plate carrying the bobbins, are effected in the usual manner. 95

In accordance with my invention I make use of the usual flyers 2 with their spindles 3 extending beneath them while their driving pulleys or wharles 4 are at their upper 100

ends, the lower ends of the spindles 3 being arranged to take through the lifter plate 5 in well known manner.

The lifter plate 5 is arranged to carry out 5 its vertically reciprocating motions to effect the building of the coils of yarns on the bobbins in known manner and by well known cam operating devices which actuate the chain 6 that encircles the pulley 7. This 10 pulley 7 is mounted so that it may be detached from the shaft 8 during the doffing operations, while its coupling to said shaft is effected for carrying out the usual spinning process, by devices hereinafter described.

Fixed upon the shaft 8 and adjoining the chain guiding pulley 7, is a spur wheel 9 which meshes with a pinion 10 and this pinion is fixed upon the hub of a hand 20 wheel 11 so that when the operative actuates said hand wheel 11 he may actuate the wheel 9.

To couple the pulley 7 to the wheel 9 I employ a clutch bolt 12 which I mount to 25 slide upon one or other of the arms of the wheel 9 so that by the handle devices 12^a said bolt 12 may be made to engage with the pulley 7 in order to couple same to the wheel 9 to enable said wheel to transmit 30 motion from the pulley 7 to the shaft 8 during the spinning of the yarn and the winding of same in coils upon the bobbins in well known manner.

The hand wheel 11 and its pinion 10 are 35 mounted upon a stud 11^a supported by appropriate bearings fixed to the end frame A.

The lifter plate 5 is connected to and is operated by the usual chain devices which are made to encircle chain pulleys fixed upon 40 the shaft 8 in several positions throughout the length of said shaft 8 in order to meet the requirements of a longer or shorter lifter plate 5 according to the number of spindles in the machine, as is well understood.

The drag cords 14, are connected at the rear of the spindles 3, to a sliding rod 14^a and to the front of the spindles to another notched sliding rod 14^b (see Figs. 2 and 3) 50 so that during the spinning operations their weights 14^c may cause said drag cords 14 to press against the edges of the lower flanges of the bobbins 13 in well known manner.

As is well known, the drag on the bobbins 13 during the building operations has to be increased and to effect this increase the drag cords are gradually moved to press more firmly against the flanges of the bobbins as 60 the coils of yarn thereon increase in diameter. To secure this increase of drag action I employ the well known ratchet wheel and worm devices (not shown in the drawings) which move the two sliding bars 14^a and 14^b from right to left in order to

cause the drag cords 14 to more firmly press upon the flanges of the bobbins 13 to meet the increased leverage which the threads exercise over the bobbins upon which they have been wound as is well understood.

When the coils of yarns are being wound upon the bobbins 13 to fill said bobbins in known manner, the lifter plate 5 is raised and lowered or reciprocated in its vertical path through its usual space to control the 75 guiding of the yarns upon the bobbins from the lower to the upper ends of same throughout the spinning operations until the bobbins are filled, and during said operations the lifter plate 5 is actuated by its cam mechanism in the ordinary and usual manner during which no motion is transmitted to any other part which I employ for the doffing process hereinafter described.

In order to carry out said doffing process 85 according to my present invention I make use of the devices above explained to disengage the mechanism which actuates the lifter plate during the spinning process, to allow said lifter plate to be separately operated to effect the "doffing."

As means for performing these "doffing" actions, I fix cams upon the shaft 8 for effecting the further and necessary movements. That is to say, to secure the levelling or adjusting of the flyers 2 I mount a cam 16 (shown by Figs. 5, 12 and 13 and hereinafter more fully described) upon the shaft 8 and this cam 16 is arranged, by the lever 16^a, to move a bar 16^b which is carried upon the end of the lever 16^a that is supported by bearings 16^c fixed to the framework of the machine. This bar 16^b extends longitudinally the length of the machine to be supported by other lever arms (similar to 16^a) 105 also mounted upon fixtures carried by the framework of the machine, thus the bar 16^b may be moved longitudinally by its cam 16 and will be supported by the levers 16^a throughout its longitudinal movement.

On the bar 16^b are pivoted two or more levers 16^e, according to the length of the machine, and the rear ends of the levers 16^e are actuated by a spring 16^f which keeps or tends to keep said lever 16^e in their advanced 115 positions. The levers 16^e are sufficient in number to support another bar 16^f which extends the full length of the machine in order that the inclines α on the front edge of said bar 16^f may come in contact with the legs 120 of the flyers 2 somewhat as is shown by Fig. 5, by which means when the cam 16 is rotated by the shaft 8 it will actuate the whole series of flyers 2 to bring their legs into or approximately into the same vertical plane.

Also fixed on the shaft 8 is another cam 17 (of a formation hereinafter described) and this cam 17 actuates the lever 17^a (which is pivoted upon the framework of the machine) so that said lever 17, may, by the rod 130

17^b actuate a lever 17^c which is fixed upon a shaft 17^a.

This shaft 17^a is supported by the frame-work of the machine and has a series of arms 5 17^e fixed upon it, the number of said arms being sufficient to carry or support a longitudinal shaft 17^f which is swivelled on the outer ends of same.

Upon this swivelling shaft 17^f (which is 10 preferably square in cross section) are mounted bifurcated members 17^g (corresponding in number with that of the spindles 3) which will when being moved, span the spindles 3 so as to wipe or carry 15 away the coils of threads extending from the legs of the flyers and encircling said spindles 3 after the full bobbins have descended beyond the lower ends of same as is well known.

20 In an appropriate position upon this square shaft 17^f is fixed a lever 17^h (see Fig. 10) so that a stud 17^k extending laterally therefrom may take beneath a cam piece 17^m fixed upon a bracket 17^p which is secured to 25 the frame-work of the machine. Thus as the cam 17 is rotated (as is hereinbefore described), and as it is carried by the shaft 8, the lever 17^a will cause the levers 17^b and 17^c and said shaft 17^a to oscillate. This oscillation of the shaft 17^a by the actions of 30 the cam 17 brings the arms 17^e so that the shaft 17^f carrying the bifurcated member 17^g will cause these latter to span the spindles 3 as is shown by Fig. 9. The motion 35 transmitted to the shaft 17^f in this forward direction is such as to cause said shaft to carry its lever 17^h in order that the stud 17^k will pass the lower end of the cam piece 17^m at the point *b* (Fig. 10). Here it will encounter the hinged piece 17^s which is free 40 to move from the position shown in full lines to the position shown in broken lines of Fig. 10 by which means as the shaft 17^f is moving downwardly the bifurcations 17^g will extend horizontally as they descend over the spindles 3 to carry the coils of yarn beyond the lower ends thereof. However, on reaching the point where the hinged plate 17^s will engage with the stud 17^k the actions 45 of the cam 17 upon the stud 17^k are reversed during the reverse movement of the shaft 8 as is hereinafter described, and at this time the shaft 17^f will be tilted so that the bifurcations 17^g will ascend to their positions 50 shown by Fig. 14 by passing through a path which lies clear of the lifter plate 5, the spindles and any bobbins that may be mounted thereon. This is effected by the stud 17^k following the contour of the cam piece 17^m 55 until its normal position (as shown by Fig. 10) is reached.

Fixed upon the same shaft 8 is another cam 18 (formed as hereinafter described) which operates the lever 18^a and this lever 60 18^a is connected by a rod 18^b to a lever 18^c

fixed upon a longitudinal shaft 18^d. This shaft 18^d extends lengthwise the machine and has fixed upon it the arms 18^e. At the upper ends of these arms 18^e is fixed a longitudinal rail 18^f and upon this longitudinal rail are fixed a series of bobbin engaging members 18^g. These members 18^g are for 70 engaging the upper flanges of the bobbins 13 as shown by Fig. 14 as well as acting as displacers for the full bobbins. 75

To enable the member 18^g to engage with the bobbins 13 slots *c* (see Fig. 4) are formed laterally in said members 18^g to span the barrel parts of the bobbins 13 and yet to carry the upwardly projecting flanges *d* which 80 extend from the engaging members 18^g to receive and overhang the flanges of the bobbin, also shown by Fig. 14.

The cam 18 is arranged to have a part of 85 its surface to occupy a normal position shown by Fig. 15, during the spinning operations and in said normal position the engaging members 18^g may have placed upon them the empty bobbins 13 as is shown by Figs. 14 and 15 while when the cam 18 is 90 rotated by the shaft 8 said members 18^g may be moved from the said front position shown in full lines Figs. 14 and 15 to the rear positions shown in broken lines by Fig. 15 where all the bobbins will be held clear 95 of the spindles 3 and lifter plate 5. This extension 18^h from the rail 18^f to the rear of the barrels of the bobbins 13 are employed so that they may support the bobbins in a lateral direction and keep them in proper 100 position, as is shown in broken lines Fig. 15 to enable them to clear or push away the full bobbins as is hereinafter described. 105

The lifter plate 5 is actuated by the known devices hereinbefore explained and is 110 provided with known means whereby the longitudinal bars to which the drag cords 14 are secured are caused to advance as is set forth. During their advancing movements they will carry with them the bracket 19 at the lower end of which is pivoted a small runner 19^a so that said runner may take into the groove in a fixed cam plate or member 19^b. 115

When the operating parts are in the position shown by Fig. 1 the advancing of the cord bars 14^a and 14^b are permitted by the bowl or runner 19^a moving within the broader grooved part 19^d of the cam plate 19^b. However, when the doffing operations 120 are to commence said runner or bowl 19^a on descending with the lifter plate 5 will come in contact with the inclined edge *d*¹ of the cam groove 19^d and will be thereby caused to travel longitudinally to carry with it its bracket 19 and the cord bars 14^a and 14^b until said bowl 19^a reaches the straight groove *d*² in the same plate 19^d. 125

This movement of the bars 14^a and 14^b will have carried all the cords clear of the 130

flanges of the lower end of the bobbins and when the attendant readjusts the lifter plate 5 into its working position as is shown by Fig. 1 the bowl 19^a, will, by coming in contact with the inclined part d^3 of the cam plate 19^b, have caused the bars 14^a and 14^b to move from their position where the cords were clear of the bobbins so as to bring same bars and their cords into the desired position against the edges of the bobbins on reaching the position shown by Fig. 1 in which case all of the cords are readjusted into position so as to place the least amount of drag required upon the bobbins 13 at the commencement of the spinning operation, the increasing of said drag being effected by the devices hereinbefore described.

While the shaft 8 is being oscillated to carry out the vertical reciprocations of the lifter plate 5 during the process of spinning, the cam 16 is not moved sufficiently far to bring its cam surface to act upon the lever 16^a hence during said process of spinning said lever 16^a and all the parts it moves or operates, are stationary. In like manner and during the same actions the operating grooves in the cams 17 and 18 permit these latter to be moved by the shaft 8 without bringing their cam surfaces into action, thus at this time the devices they actuate remain in their normal inoperative positions.

The operations of the several parts are as follows:—

After the bobbins 13 have been filled with the coils of yarn as is shown by Figs. 14 and 15, and at the same time the series of empty bobbins 13^a have been placed by the attendant upon their engaging members 18^a, the attendant will disengage the coupling bolt 12 by actuating the handle 12^a so as to free the pulley 7 from its connections with the shaft 8. He may then actuate the hand wheel 11 and by the pinion 10 and wheel 9, cause the shaft to revolve in order to lower the lifter plate 5 beyond the position where the upper ends of the full bobbins 13 would be clear of the lower ends of the flyers as is shown by Figs. 12 and 13. After this position is reached by continuing the motions of the hand wheel 11 the lifter plate 5 will continue to descend and simultaneously with the descending of this lifter plate 5 the cam 16 will now have brought the flyer operating bar 16^c into its position shown by Fig. 5 so that all the flyers are adjusted in the desired position.

Shortly after the adjusting of the flyers in the position described, the cam 17 will have operated the shaft 17^c so that the bifurcations 17^b will engage with the spindles 3 by spanning same; thus on descending they will remove any coils of yarn that may be encircling said spindles 3, and the continued motion of the bifurcations 17^b will carry

said yarns beyond the lower ends of the spindles. Simultaneously with the actions of the cam 16 to bring the legs of the flyers into alignment, and commencing at about the same time, the cam 18 will actuate the bobbin engaging members 18^a and will remove same from their positions shown in full lines Figs. 14 and 15 to the rear position shown in broken lines of Fig. 15 so that said bobbins 13^a are moved clear of the lifter plate 5 during its descent. After the lifter plate 5 has descended with its full bobbins past where the empty bobbins are shown in broken lines Fig. 15 down to its lowest position, the cam 18 will, by continuing in motion cause the members 18^a to advance from their rear position shown in broken lines Fig. 15 to the position shown in full lines by said Fig. 15, there they will have encountered the full bobbins and will have pushed same off the lifter plate 5 as is shown in broken lines Fig. 15 in order that they will descend into a trough or receptacle 20 which extends the length of the machine.

When the empty bobbins 13^a have reached this last named position with all the full bobbins cleared away from the lifter plate, the attendant will reverse the direction of motion of the hand wheel 11 and will thereby reverse the motions of the shaft 8 in order to carry these several cams back to the normal positions which they occupy during the spinning operations, and in doing this the lifter plate will move from its position shown in broken lines by Figs. 14 and 15 to raise the empty bobbins 13^a onto the lower ends of the spindles 3 and so soon as said bobbins 13^a have been moved for a sufficient space over the ends of the spindles 3, the cam 18 will again cause the bobbin engaging members 18^a to move to the rear of the lifter plate 5 in order to permit said lifter plate to rise into its operating position above said engaging members 18^a.

When the lifter plate 5 has thus ascended above the members 18^a these latter will return to their normal forward positions where again the bifurcations may (afterwards and after the spinning process has been commenced) receive their supply of empty bobbins as will be understood. On the lifter plate 5 being further raised, by the movement of the hand wheel 11 carrying the wheel 9 into position for the engaging bolt 12 to engage with the pulley 7, all the doffing operations will have been completed and every part of the doffing mechanism will have been re-adjusted in its respective position ready for the spinning operations to be re-started.

The machine is then put into motion until a few coils of yarn are wound upon the newly supplied empty bobbins, when the machine is again arrested, all the loose or extending yarns from the bobbins on the spindles 3 to those in the receptacle 20 (see Fig. 130

13) will extend over a longitudinally grooved bar 21 across the groove 21^a in which are made other grooves 21^b (see Fig. 12) equal in number to the spindles in the machine 5 and therefore to the threads that extend therefrom.

Before starting the machine into further action the attendant carries the blade of a knife along the groove 21^a in this bar 21 10 and by the cross grooves 21^b receiving the yarns all of said yarns are cut and the machine may then be fully started into action.

When the spinning, doubling, twisting and like machine is provided with brake 15 and clutch coupling devices for the spindles it may occur from time to time that certain of said brake devices and coupling means are in such positions as to retard or hinder the flyers and their spindles from revolving 20 so that difficulty might arise when the flyer adjusting mechanism was brought into use. To avoid this I make use of a rod 30 (see Figs. 10 and 11) which I fix upon the ends of levers 31 so that said rods 30 may extend 25 above the operating handle devices 32 which actuate the brake and coupling mechanism described. The lever 31 at the end of the machine shown is pivoted at 31^a and is coupled by a rod 33 to a lever 34 pivoted 30 at 35 so that a bevel wheel or quadrant 36 fixed to said lever 34 may engage with another bevel wheel 37 that is fixed to a horizontal lever 38. This lever 38 is connected 35 to the starting rod 39 that extends lengthwise the machine so that immediately the attendant operates the starting handle 40 to stop the machine prior to doffing, the shaft 40^a will oscillate and cause the lever 41 also to oscillate. To this lever 41 is connected 40 the rod 39 hence the oscillating of the lever 41 will cause said rod 39 to be moved longitudinally to operate the lever 38 so as to depress the longitudinal rod 30 thereby relieving all the handle devices which operate 45 the clutches and brake mechanism so that the flyers 2 and their spindles 3 may then be rotated freely.

The receptacle 20, which receives the full bobbins when same are forced forward to 50 fall from the lifter plate is of the formation shown by Fig. 13, and is arranged to be supported by a series of brackets 42 which extend from the framework of the machine.

From the rear lower edge of this receptacle 55 20 a projection 43 extends which carries a bowl 44. This bowl takes into a guiding slot 45 so that as the extending end of a hand actuated lever (not shown by the drawings) moves the rod 46 which is coupled to 60 it and to a bracket 47 on the receptacle 20, in a rearward direction, said receptacle 20 will be moved from the position shown in full lines Fig. 13 (where it will receive the full bobbins) into the position shown in 65 broken lines of the same figure and in this

position may be used as a platform for the attendant to step upon when reaching articles from the upper parts of the machine.

Such being the nature and object of my said invention what I claim is:—

1. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said lifter plate, cam mechanism for automatically operating the lifter plate during the process of building, coupling means for connecting hand operated devices to said shaft, said hand operated devices, bifurcated members for laying hold of the bobbins when supported by the lifter plate, a rail supporting said bifurcated members, a shaft and connections therefrom to support and operate said rail, lever devices for connecting said shaft to cam mechanism, a cam device for operating said levers to cause the bifurcated members to lay hold of the bobbins and to 70 recede with said bobbins, cam mechanism for removing coils of yarn from off the spindles when the bobbins have been discharged therefrom, and means for operating said cam devices.

2. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said lifter plate, cam mechanism for automatically operating the lifter plate during the process of building, coupling means for connecting hand operated devices to said shaft, said hand operated devices, bifurcated members for laying hold of the bobbins when supported by the lifter plate, a rail supporting said bifurcated members, a shaft and connections therefrom to support and operate said rail, lever devices for connecting said shaft to cam mechanism, a cam device for operating said levers to cause the bifurcated members to lay hold of the bobbins and to recede with said bobbins, cam mechanism for removing coils of yarn from off the spindles when the bobbins have been discharged therefrom, means for operating 100 said cam devices, and cam actuated rod devices for bringing the legs of the flyers into alignment.

3. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said 125 lifter plate, cam mechanism for automatically operating the lifter plate during the process of building, coupling means for connecting hand operated devices to said shaft, said hand operated devices, bifurcated members for laying hold of the bobbins when supported by the lifter plate, a rail supporting said bifurcated members, a shaft and connections therefrom to support and operate said rail, lever devices for connecting said shaft to cam mechanism, a cam device for operating said levers to cause the bifurcated members to lay hold of the bobbins and to recede with said bobbins, cam mechanism for removing coils of yarn from off the spindles when the bobbins have been discharged therefrom, means for operating 130 said cam devices, and cam actuated rod devices for bringing the legs of the flyers into alignment.

cally operating the lifter plate during the process of building, mechanism for removing the drag cords from the bobbins, means for returning said drag cords into contact with their bobbins, coupling means for connecting hand operated devices to said shaft, said hand operated devices, bifurcated members for laying hold of the bobbins when supported by the lifter plate, a rail supporting said bifurcated members, a shaft and connections therefrom to support and operate said rail, lever devices for connecting said shaft to cam mechanism, a cam device for operating said levers to cause the bifurcated members to lay hold of the bobbins and to recede with said bobbins, cam mechanism for removing coils of yarn from off the spindles when the bobbins have been discharged therefrom, means for operating said cam devices and cam actuated rod devices for bringing the legs of the flyers into alignment.

4. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said lifter plate, cam mechanism for automatically operating the lifter plate during the process of building, mechanism for removing the drag cords from the bobbins, means for returning said drag cords into contact with their bobbins, coupling means for connecting hand operated devices to said shaft, said hand operated devices, bifurcated members for laying hold of the bobbins when supported by the lifter plate, a rail supporting said bifurcated members, a shaft and connections therefrom to support and operate said rail, lever devices for connecting said shaft to cam mechanism, a cam device for operating said levers to cause the bifurcated members to lay hold of the bobbins and to recede with said bobbins, cam mechanism for causing the rail and bifurcations to advance with the empty bobbins to push the full bobbins off the lifter plate, cam mechanism for removing coils of yarn from off the spindles when the bobbins have been discharged therefrom, means for operating said cam devices, and cam actuated rod devices for bringing the legs of the flyers into alignment.

5. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said lifter plate, cam mechanism for automatically operating the lifter plate during the process of building, a shaft for operating

said mechanism, coupling means for connecting hand operated devices to said shaft, said hand operated devices, a cam on said shaft for longitudinally sliding a bar having inclines for contacting with the legs of the flyers, spring actuated levers for supporting said bar and operating it in the reverse direction, bifurcated members carrying the empty bobbins, means for operating said members to displace the full bobbins by the empty bobbins, a receptacle for receiving the full bobbins that are displaced, means for actuating said receptacle and means for severing the threads extending from the flyers to the full bobbins.

6. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said lifter plate, cam mechanism for automatically operating the lifter plate during the process of building, coupling means for connecting hand operated devices to said shaft, said hand operated devices, a cam on said shaft for longitudinally sliding a bar having inclines for contact with the legs of the flyers, spring actuated levers for supporting said bar and operating it in the reverse direction, fork devices for spanning the spindles, a rod carrying said fork devices, duplex lever arms for supporting said rod, cam mechanism for carrying said rod with its forked members in a different path when receding to its normal position to that through which it moves in the advancing position, bifurcated members carrying the empty bobbins, means for operating said members to displace the full bobbins by the empty bobbins, a receptacle for receiving the full bobbins that are displaced, means for actuating said receptacle and means for severing the threads extending from the flyers to the full bobbins.

7. In doffing apparatus for spinning and like machines, bobbins arranged to take over the spindles of said machines, said spindles, a lifter plate for raising and lowering the bobbins upon the spindles, an oscillating shaft for transmitting motion to said lifter plate, connections from said shaft to said lifter plate, cam mechanism for automatically operating the lifter plate during the process of building, coupling means for connecting hand operated devices to said shaft, said hand operated devices, a cam on said shaft for longitudinally sliding a bar having inclines for contact with the legs of the flyers, spring actuated levers for supporting said bar and operating it in the reverse direction, bifurcated members carrying the empty bobbins, means for operating said members to displace the full bobbins by the

empty bobbins, a receptacle for receiving the full bobbins that are displaced, means for actuating said receptacle, means for severing the threads extending from the flyers to the full bobbins, cranked rod devices for actuating the clutch couplings and brake mechanisms which transmits motion to and ar-

rest the motions of the spindles, quadrant devices and rod connections for transmitting motion to said disengaging bar, and hand lever devices for operating said rod and lever connections. ¹⁰

SAMUEL MOORHOUSE.
